FIG. 1.

FIG. 3.

FIG. 4.

FIG. 6. 5 3

1 FIG. 5. 3

Bryant & Loring
ATTORNEY'S

UNITED STATES PATENT OFFICE

OSCAR DOLEJAL, OF KANSAS CITY, KANSAS

GARTER

Application filed April 8, 1929. Serial No. 353,610.

This invention relates to certain new and useful improvements in garters and has for one of its objects to provide a garter or hose supporter comprising a single continuous 5 length of elastic fabric having a single point of connection with a sock or stocking at one of its ends and an interlocking connection between the other end of the elastic and an intermediate portion thereof.

10 A further object of the invention is to provide a garter wherein a metallic clip of U-shaped construction has one end of an elastic strip or band associated therewith in a manner to prevent contact between the 15 metal clip and leg of the wearer with a single sock or stocking attachment at one end of the elastic while an intermediate portion of the elastic is inserted between the legs of the U-shaped clip to form a band 20 encircling the leg of the wearer.

With the above and other objects in view that will become apparent as the nature of the invention is better understood, the same consists in the novel form, combination and 25 arrangement of parts hereinafter more fully described, shown in the accompanying drawing and claimed.

In the drawing:—

Figure 1 is a perspective view of a garter 30 constructed in accordance with the present invention showing a single continuous length of elastic having a binding and elastic guide strip at one end and a hose attaching clasp at its other end;

35 Figure 2 is a schematic view showing the garter in use;

Figure 3 is a detail sectional view taken on line 3—3 of Figure 2 showing the U-shaped clip at one end of the elastic strip 40 covered by the strip to prevent contact between the clip and leg of the wearer and with an intermediate portion of the strip included between the clip;

Figure 4 is a detail sectional view taken on line 4—4 of Figure 1;

Figure 5 is a developed plan view of the clip;

Figure 6 is a perspective view of the folded clip before the elastic strip has been 50 attached thereto;

Figure 7 is a longitudinal sectional view taken on line 7—7 of Figure 6; and

Figure 8 is a cross-sectional view, similar to Figure 4 of another form of clip.

In the form of the invention shown in 55 Figures 1 to 7, there is provided a metallic strip formed from a blank 1 as shown in Figure 5 that is foldable upon the dotted line 2 with a cross-slot 3 in one end of the blank through which the elastic tape 4 is insertable. 60 The blank 1 shown in Figure 5 is folded into U-shape as shown in Figure 6 to provide side plates 5 having a closed end 6 and an open end 7, the cross slot 3 appearing in one end of a side plate 5 adjacent the opening 7. 65

The tape 4 has one end thereof inserted through the opening 3 from a point between the side plates 5 with the extended end thereof folded around the outer sides of the plates 5 and with the terminal end folded inwardly between the plates as shown in Figure 4 and suitably retained in position by an adhesive or in any preferable manner, the association of the tape end with the clip being shown more clearly in Figure 4. The 70 opposite end of the elastic tape 4 carries a sock or stocking engaging clasp 8.

In the use of the device, the U-shaped clip is preferably positioned at one side of the leg as shown in Figure 2 and the tape wound 80 around the leg and inserted between the spaced plates 5 as shown in Figure 3, the clasp 8 thereof extending downwardly for engagement with the sock S or stocking as illustrated. By enclosing the metallic clip with one end of the elastic tape 4, contact between the metallic clip and leg of the wearer is prevented, the finished article presenting an exceptionally neat appearance and being effectively retained in its adjusted position insures proper support for the sock or stocking S.

In the form of the invention shown in Figure 8, the side plate 5^a of the clip opposite to the plate provided with the slot 3 is 95 formed with a pair of spaced transverse slots 9 intermediate the ends of the plate 5^a through which the terminal end of the elastic tape 4 is threaded to form another form of anchorage for the end of the elastic tape. 100

In other respects, the garter is of identical construction and presents a device which eliminates the contact of a metal fastener with the leg of the wearer.

From the above detailed description of the device, it is believed that the construction and use thereof will at once be apparent, and while there are herein shown and described, the preferred embodiments of the present invention, it is nevertheless to be understood that minor changes may be made therein without departing from the spirit and scope of the invention as claimed.

I claim:—

15 A garter comprising an elastic strip, a U-shaped metallic clip at one end thereof, the legs of the clip being of the same length and one of said legs having a transverse slot therein adjacent the open end of the clip, the elastic strip having one end insertible through the slot from between the sides of the clip and extended to enclose the outer sides of the clip legs with the terminal end of the elastic strip folded inwardly between 20 the clip legs, the other clip leg having a pair of spaced transverse slots between the ends thereof, said terminal end of the elastic strip being threaded through the spaced slots and 25 a hose attaching clasp at the other end of the elastic strip.

30 In testimony whereof I affix my signature.

Dr. DOLÉJAL, OSCAR.
